UNITED STATES PATENT OFFICE.

CHARLES E. WIRTH, OF WATERBURY, CONNECTICUT, ASSIGNOR TO THE PLUME & ATWOOD MFG. CO., OF WATERBURY, CONNECTICUT, A CORPORATION OF CONNECTICUT.

LAMP-BURNER.

No. 901,139.

Specification of Letters Patent.

Patented Oct. 13, 1908.

Application filed April 10, 1908. Serial No. 426,174.

To all whom it may concern:

Be it known that I, CHARLES E. WIRTH, a citizen of the United States, residing at Waterbury, in the county of New Haven and State of Connecticut, have invented an Improvement in Lamp-Burners, of which the following is a specification.

My invention relates to an oil or fluid font lamp and burner employing an incandescent mantle, and the object of my invention is to increase and make more efficient the air carrying capacity of the burner and therefore the condition and heat carrying capacity of the flame and illumination or incandescence of the mantle.

In the device of my invention the outer wick tube is made with a flanged ring at the upper end; a foraminous inner deflector surrounding this wick tube is provided with an in-turned flange at the upper end in the same plane with said flanged ring and slightly spaced apart therefrom so as to leave an annular opening between their juxtaposed edges for an air supply to the flame.

The upper end of this deflector is provided with series of circumferentially placed perforations. The lower end is flat and also provided with series of perforations and this lower end fits within the burner proper.

I provide a conical deflector that is imperforate. It is made with an in-turned flange at the upper end which flange comes appreciably above the flange of the inner deflector. This conical deflector is secured as one with a spring chimney holder of usual construction.

The outer edge of the burner is notched at intervals and the lower peripheral edge of the conical deflector is made with tongues to pass through these notches so that upon a partial rotation of the deflector and the chimney holder the same are removably secured to the burner.

Within the central draft tube of the lamp are suitable supports for a deflector and the conical deflector member is provided with means by which a standard or bar is secured and supported and from which the mantle is hung, and I provide means for indicating the extent to which the wick has been raised for use, all of which is hereinafter more particularly described.

In the drawing, Figure 1 is a vertical central section through the burner and an elevation of the major portion of the mantle

and its support. Fig. 2 is a plan of the burner with the conical deflector and spring chimney holder removed. Fig. 3 in larger size is a partial section and elevation of the upper part of the burner showing the special features of my invention. Fig. 4 is a section in large size through the parts of the burner where the conical deflector is removably connected to the base of the burner body. Fig. 5 is an elevation of the edge of the burner showing one of the notches. Fig. 6 is an elevation and Fig. 7 a section and partial elevation of the means for determining the extent to which the wick is raised.

Referring particularly to Fig. 1, a represents the oil font, a^1 the central draft tube; b the burner body of usual perforated construction; b^1 is the wick tube formed therewith and by a screw joint 2 removably connected with the oil font a . Within this wick tube is the usual form of tubular rack b^2 actuated longitudinally within the wick tube by the pinion c on the shaft c^1 and turned by the disk c^2 . The upper end of the wick tube b^1 is exteriorly provided with a flanged ring 3.

d represents the inner deflector made with a cylindrical upper end, a flat base and conical union with a flange 4 in-turned at the upper end. This flange 4 comes closely adjacent in its position to the edge of the flanged ring 3 and is in the same plane therewith so that between the juxtaposed edges of the two flanges there is an annular opening providing a narrow air passage to the flame. The lower horizontal part of this deflector d is provided with a series of perforations 5 and at the upper part with a series of perforations 6 and the periphery of the lower part of the deflector is preferably turned down as a flange and made to fit snugly within the rim at the upper end of the burner body b . Notwithstanding the fact that this inner deflector is of thin metal it is rendered very stiff and rigid by virtue of its construction and because of its peripheral flange and the flange 4.

e represents a conical deflector surrounding and spaced apart from the inner deflector d . It is provided at its upper end with an in-turned flange e^1 which comes at a predetermined distance above the flanges 3 4. The opening in this flange e^1 agrees substantially with the inner diameter of the wick tube b^1 .

- f* represents a spring chimney holder of usual construction secured preferably by rivets to the conical deflector *e*. The lower portion of this conical deflector *e* is preferably provided with ribs *7* on its flat portion against which the lower end of the chimney *m* bears when the chimney is in place, thereby creating numerous small channels for the passage of air beneath the chimney to the outside of the mantle *k*. This mantle is supported by a standard wire *k*¹ in the usual manner with its lower end passing into an opening and secured by a thumb screw *k*².
- Within the central draft tube *a*¹ I have shown ring supports *g* *h* and a standard *h*¹ connected thereto and upon which is placed a deflector. This deflector for the particular purposes of my invention and for convenience, I prefer to construct with the three parts *i* *i*¹ and *i*²; that is, *i* is the upper cup-shaped part, *i*¹ a center disk and *i*² a tubular body to which the parts *i* and *i*¹ are connected and which fits over and is supported by the standard *h*¹.
- l* represents the wick. I have shown upon the pinion shaft *c*¹ sleeves *n* and *o*; the sleeve *n* is made fast to the wick tube and passes through the burner body and serves as a bearing, and the sleeve *o* secured to the shaft *c*¹ by the clamp screw *o*². On the sleeve *n* and at right angles thereto is a pointer *n*¹ and a similar pointer *o*¹ on the sleeve *o*; the parts *o* *o*¹ and *o*² having an adjustable relation to the parts *n* *n*¹ and said parts are provided to come into alinement or coincidence at such a time as the wick may be raised into the desired position for use. These parts will be adjusted as the wick is burned down and trimmed.
- The burner body *b* is provided with equidistant spaced apart notches *8* in its periphery, (see Figs. 2, 4 and 5) and the lower portion of the conical deflector is provided with tongues *9* and when the parts are brought together, the tongues *9* pass through the notches *8* in bringing the conical deflector down upon the upper edge of the burner. The conical deflector is then given a slight turn so as to bring the tongues beneath its full periphery so as to clamp said parts together.
- The essential object of my invention is to increase and make more efficient the air carrying capacity of the burner and to even supply to the burner more air than is needed to produce the usual light giving flame. This will tend to heat and vaporize the fluid at the upper end of the wick and to cause a flame of burning vapor more than a flame of burning fluid, and the same as effected in the construction shown and described, tends to force the flame outward against the mantle and to render the mantle incandescent; and in the operation of the device of my improvement and with special reference to Fig.
- 1, air enters beneath the chimney to the outside of the mantle. Air also enters through the perforations of the burner *b* and divides—part of it going through the lower perforations at *5* of the inner deflector *d* 70 and part through the upper perforations *6*. Because the deflector *e* is imperforate all the air passing through the perforations *5*, ascends between the two deflectors, commingles with the air passing through the perforations *6* and through the annular opening between the flanges *3* and *4*. The air that passes up through the center draft tube *a*¹ is deflected in part by the member *i*¹ and mainly by the member *i*. The result of these air currents is first to supply an excess quantity of air, to cause a heating of the upper end of the wick tube and the flanged ring *3*, part of the fluid from the wick passing off onto the flanged ring and being converted 85 into vapor. By these air currents the flame of the burning fluid and vapor is given about the form shown in Fig. 3, spreading over toward the mantle and heating the same to incandescence. 90
- I claim as my invention:
1. In a lamp burner the combination with an outer wick tube, of a flanged ring surrounding the same at the upper end, an inner deflector having an in-turned flange at the upper end in the same plane as the flanged ring of the wick tube and slightly spaced apart therefrom so as to leave between the parts a narrow annular aperture. 95
  2. In a lamp burner the combination with an outer wick tube, of a flanged ring surrounding the same at the upper end, an inner deflector having an in-turned flange at the upper end in the same plane as the flanged ring of the wick tube and slightly spaced apart therefrom so as to leave between the parts a narrow annular aperture, 100 and a series of perforations in the upper part of the inner deflector below the in-turned flange thereof. 110
  3. In a lamp burner the combination with an outer wick tube, of a flanged ring surrounding the same at the upper end, an inner deflector having an in-turned flange at the upper end in the same plane as the flanged ring of the wick tube and slightly spaced apart therefrom so as to leave between the parts a narrow annular aperture, 115 said internal deflector having a flat outer portion, a series of perforations therein and 120 constructed with a flanged periphery for support and stiffness.
  4. In a lamp burner the combination with an outer wick tube, of a flanged ring surrounding the same at the upper end, an inner deflector having an in-turned flange at the upper end in the same plane as the flanged ring of the wick tube and slightly spaced apart therefrom so as to leave between the parts a narrow annular aperture, 125 130

and an outer conical deflector member surrounding and spaced apart from the inner deflector and having an in-turned flange at the upper end, the opening of which agrees substantially in diameter with the diameter of the wick tube and spaced above the upper end of the wick tube and its flanged ring.

5. In a lamp burner the combination with an outer wick tube, of a flanged ring surrounding the same at the upper end, an inner deflector having an in-turned flange at the upper end in the same plane as the flanged ring of the wick tube and slightly spaced apart therefrom so as to leave between the parts a narrow annular aperture, and a series of perforations in the upper part of the inner deflector below the in-turned flange thereof, and an outer conical deflector member surrounded and spaced 10 apart from the inner deflector and having an in-turned flange at the upper end, the opening of which agrees substantially in diameter with the diameter of the wick tube and spaced above the upper end of the wick tube 15 and its flanged ring.

6. In a lamp burner the combination with an outer wick tube, of a flanged ring surrounding the same at the upper end, an inner deflector surrounding the wick tube having an in-turned flange at its upper end in the same plane as the flange surrounding the wick tube and spaced apart therefrom so as to provide between the parts a narrow annular air aperture, a support in the burner 20 for said inner deflector, a conical deflector spaced apart from and surrounding the inner deflector and at its upper end having an in-turned flange raised above the upper end of the inner deflector and having an opening 25 agreeing substantially in diameter with the opening in the wick tube, a central draft tube and devices therein forming a support, and a deflector device carried thereby and extending above and over-reaching the upper end of the wick.

45 per end of the wick.

7. In a lamp burner the combination with

an outer wick tube, of a flanged ring surrounding the same at the upper end, an inner deflector surrounding the wick tube having an in-turned flange at its upper end in the same plane as the flange surrounding the wick tube and spaced apart therefrom so as to provide between the parts a narrow annular air aperture, a support in the burner for 50 said inner deflector, the upper end of the inner deflector and the lower portion thereof being each provided with series of perforations for the passage of air therethrough, a conical deflector spaced apart from and surrounding the inner deflector and at its upper 55 end having an in-turned flange raised above the upper end of the inner deflector and having an opening agreeing substantially in diameter with the opening in the wick tube, a central draft tube and devices therein forming a support, and a deflector device carried thereby and extending above and over-reaching the upper end of the wick.

8. In a lamp burner the combination with the outer wick tube, of a flanged ring surrounding the same at the upper end, an inner deflector surrounding the wick tube having an in-turned flange at its upper end in the same plane as the flange surrounding the wick tube and spaced apart therefrom so as 70 to provide between the parts a narrow annular air aperture, a support in the burner for said inner deflector, the upper end of the inner deflector and the lower portion thereof being each provided with series of perforations for the passage of air therethrough, a conical deflector spaced apart from and surrounding the inner deflector and at its upper 75 end having an in-turned flange raised above the upper end of the inner deflector and having an opening agreeing substantially in diameter with the opening in the wick tube.

Signed by me this 4th day of April, 1908.
